(57) **CLAIM**

The ornamental design for a combined bollard and light fixture, as shown and described.

DESCRIPTION

The file of this design patent application contains two photographs executed in color.

FIG. 1 is a photograph of a perspective view of the combined bollard and light fixture, the left side being identical with the right side as shown and the back being identical with the front as shown, color but not the specific wavelength of light for the wash forming a part of the design, the color of the surface of the combined bollard and light fixture not forming a part of the design; and,

FIG. 2 is a photograph of a front view inclined from above of the combined bollard and light fixture, the back being identical with the front as shown, color but not the specific wavelength of light for the wash forming a part of the design, the color of the surface of the combined bollard and light fixture not forming a part of the design.

The bottom view does not form part of the design. All top surfaces are visible in the other views.
